UNITED STATES PATENT OFFICE.

ROBERT M. GILSON, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed September 22, 1926. Serial No. 136,931.

My invention relates to railway traffic controlling apparatus, and particularly to apparatus of the type comprising train carried governing means controlled by energy 5 received from the trackway. More particularly my present invention relates to the trackway portion of such apparatus.

I will describe one form of trackway apparatus embodying my invention, and will 10 then point out the novel features thereof in claims.

The accompanying drawing is a diagrammatic view illustrating one form of trackway apparatus embodying my invention.

15 Referring to the drawing, the reference characters 1 and 1^a designate the track rails of a stretch of railway track over which traffic normally moves in the direction indicated by the arrow. These track rails are 20 divided into a plurality of successive track sections A—B, B—C, etc. by pairs of insulated joints 2. For convenience of installation it is often desirable to locate the insulated joints 2 between the ends of existing 25 rail sections. Under these conditions it usually happens that the joints of each pair are staggered and the joints are so illustrated in the drawing.

Each track section is provided with a 30 track relay designated by the reference character R with an exponent corresponding to the location and comprising two windings 7 and 8. Winding 8 of each track relay is constantly supplied with alternating current 35 from a suitable source such as an alternator M, over line wires 3 and 3^a. Winding 7 of each track relay is constantly connected across the rails adjacent the entrance end of the corresponding section. Track circuit 40 current is supplied to each section from a track transformer designated by the reference character T with a suitable exponent and having its secondary 4 constantly connected through the usual impedance 5 across 45 the rails adjacent the exit end of the section. It follows that when primary 6 of a track transformer T is supplied with alternating current as will be described herein-after, the track relay for the corresponding 50 section is energized.

Means are also provided for supplying each track section with alternating loop current which flows through the rails of the section in parallel. For this purpose each

section is provided with two impedances 12 and 13 connected across the rails adjacent the entrance end and the exit end, respectively, of the section. Each section is also provided with a loop transformer designated by the reference character L with an exponent corresponding to the location and having the terminals of its secondary 9 connected with the mid-points of the impedances 12 and 13 for the corresponding section. The primary 10 of each loop transformer is supplied with alternating current from line wires 3 and 3^a over front contact 11 of the track relay for the section next in advance. It follows that each section is supplied with loop current when and only 70 when the track relay for the section next in advance is energized.

Before explaining the operation of the apparatus it should be stated that the trackway apparatus herein shown and described 75 is suitable for, though in no way limited to, cooperation with train carried governing means arranged to give a proceed indication on board the train when the rails occupied by the train are supplied with track circuit 80 current and also with loop current. Should the supply of either track circuit current or loop current for any reason be interrupted, a stop indication is received on board the train.

As shown in the drawing, the section to the right of point C is unoccupied and track relay R^c is energized. Current is therefore supplied to primary 10 of transformer L^c and track circuit current and loop current 90 are both supplied to the rails of section B—C. A train located in section B—C would therefore receive a proceed indication.

As shown in the drawing, a train V¹ is just entering section B—C, the wheels and axles of the rear truck 20 of this train bridging the rails between the staggered insulated joints 2 adjacent point B. This train of course de-energizes relay R^b, opening front contact 11 thereon and de-energizing transformer L^b. A second train V² occupying section A—B is therefore deprived of loop current from transformer L^b and a stop indication is received on board this train.

With only the apparatus thus far described, however, and with the train V¹ in the position illustrated in the drawing, cur-

rent from transformer T^B might flow from the left-hand terminal of secondary 4 of transformer T^B , through rail 1^a of section A—B to the rear truck 20 of the train V^1 , thence through rail 1 of section B—C and through the ground to the rails 1 and 1^a of section A—B in rear of train V^2 . This current might then flow through the rails of section A—B in parallel to the forward 10 axles of the train V^2 and return to the secondary 4 of transformer T^B through rail 1 of section A—B and impedance 5. Under these conditions, that is, when current is flowing from transformer T^B over the circuit 15 just traced, alternating current flows through the rails in parallel beneath the train V^2 and this current might serve as loop current to actuate the train carried apparatus to give a false proceed indication on board the train, 20 although the section next in advance is occupied so that train V^2 should receive a stop indication. Obviously, this is a dangerous condition and in order to prevent its occurrence, I connect a source of direct current, 25 such as a battery designated by the reference character K with an exponent corresponding to the location, across the rails between the insulated joints 2 which separate each two adjacent sections. I also connect a direct 30 current checking relay, designated by the reference character D with an exponent corresponding to the location, across the rails between each pair of staggered insulated joints in parallel with the associated battery K. The primary 6 of each transformer T^B is then supplied with alternating current from line wires 3 and 3^a over a front contact 15 of the adjacent checking relay D. With this arrangement each checking relay 40 is energized by current from the adjacent battery K, except when the wheels and axles of a train occupy that portion of the track between the associated pair of joints. For example, relay D^B is normally energized but 45 is de-energized under the conditions shown in the drawing by the wheels and axles of truck 20 of the train V^1 . With the train V^1 in the position illustrated in the drawing, front contact 15 of relay D^B is open so that 50 no track circuit current is being supplied to the rails of section A—B. Train V^2 is therefore deprived of track circuit current and a stop indication is received on board the train even should the train receive false loop 55 current from an adjacent section.

A reactor 14 is interposed between each battery K and one of the track rails in order to prevent the flow of alternating loop or track circuit current from one track section 60 to the rails of an adjacent track section in sufficient magnitude to effect governing means in the latter section.

It should also be pointed out that the connections of the track transformers are such 65 that the relative instantaneous polarities of

the track circuit currents supplied to all track sections are the same, and the track relays R are arranged to be picked up by current of this polarity. Should one of the reactors 14 or one of the checking relays become short circuited, track circuit current might flow from one section into an adjacent section. For example, I will assume that checking relay D^B or reactor 14 adjacent 70 point B becomes short-circuited, thereby establishing a low impedance connection between rail 1 of section B—C and rail 1^a of section A—B. Current from transformer T^B may then flow from the left-hand terminal of secondary 4 of this transformer, through rail 1^a of section A—B to rail 1 of section B—C, thence through winding 7 of track relay R^B and return through the ground to rail 1 of section A—B and back to secondary 80 4 of transformer T^B through impedance 5. 85 But it should be pointed out that current thus supplied to relay R^B would be of a relative polarity opposite to that which can pick up the relay and the result of the stray current thus supplied to the relay would be to hold the front contact of the relay open. It follows that short circuiting of the checking relay D or a reactor 14 can not cause improper operation of an adjacent track relay. 90

Although I have herein shown and described only one form of railway traffic controlling apparatus embodying my invention, it is understood that various changes and modifications may be made therein within the scope of the appended claims without departing from the spirit and scope of my invention. 95

Having thus described my invention, what I claim is:

1. Railway traffic controlling apparatus comprising a stretch of railway track divided into a plurality of successive track sections by pairs of staggered insulated joints, a track relay for each section, means controlled by each track relay for supplying loop current to the rails of the section next in rear, a source of energy connected across the rails between the joints of each pair, a checking relay also connected across the rails between the joints of each pair, and means controlled by each checking relay for supplying track circuit current to the rails of the section next in rear. 105

2. In combination, a stretch of railway track divided into a plurality of successive track sections by pairs of staggered insulated joints, a checking relay and a source of energy connected in parallel across the rails between the joints of each pair, and means controlled by each checking relay for supplying track circuit current to the rails of an adjacent section. 110

3. Railway traffic controlling apparatus comprising a stretch of railway track divided into a plurality of successive track 115

- sections by pairs of staggered insulated joints, an alternating current track relay for each section, means controlled by each track relay for supplying alternating loop current to the rails of the section next in rear, a source of direct current and a direct current checking relay connected in parallel across the rails between the joints of each pair, and means controlled by each checking relay for supplying alternating track circuit current to the rails of the section next in rear.
4. Railway traffic controlling apparatus comprising a stretch of railway track divided into a plurality of successive track sections by pairs of staggered insulated joints, an alternating current track relay for each section, means controlled by each track relay for supplying alternating loop current to the rails of the section next in rear, a source of direct current and a reactor connected in series across the rails between the joints of each pair, a checking relay also connected across the rails between the joints of each pair, and means controlled by each checking relay for supplying alternating track circuit current to the rails of the section next in rear.
5. In combination, a stretch of railway track divided into a plurality of successive track sections by pairs of staggered insulated joints, a two-element track relay for each section, each track relay having one winding connected across the rails of the associated section and having the other winding constantly supplied with alternating current, a source of direct current and a relay connected in parallel across the rails between the joints of each pair, a reactor interposed between each such source of direct current and one rail, and means controlled by each checking relay for supplying alternating current to the rails of the section next in rear in such manner that the instantaneous relative polarity of the alternating currents supplied to all sections are the same whereby each track relay may be picked up by current from the rails of the associated section but can not be picked up by stray current from an adjacent section should a checking relay or its associated reactor become short circuited.

In testimony whereof I affix my signature.

ROBERT M. GILSON.
